UNITED STATES PATENT OFFICE.

WILLIAM R. ANDREWS, OF MYSTIC RIVER, CONNECTICUT.

IMPROVEMENT IN MECHANISMS FOR OPERATING THE HARNESS OF LOOMS.

Specification forming part of Letters Patent No. 58,968, dated October 23, 1866.

To all whom it may concern:

Be it known that I, WILLIAM R. ANDREWS, of Mystic River, in the county of New London and State of Connecticut, have invented a new and useful Mechanism for Operating the Harness of a Fancy Loom; and I do hereby declare the same to be fully described in the following specification, and represented in the accompanying drawings, of which—

Figure 1 is a top view, Fig. 2 an end elevation, and Fig. 3 a transverse and vertical section, of a loom-frame with my invention applied thereto.

In such drawings, A denotes the said frame without either the lay or the harnesses usually applied to it.

B is the lay-shaft, and C is a frame for supporting the mechanism for actuating each harness, such frame being applied to one end of the loom-frame A.

Within the frame C there is arranged, in manner as represented, two or more tri-armed levers, D D, their common fulcrum being a rod, a, going through and supported by the said frame C.

The lifting and lowering cords of each harness, after being passed about certain proper guides or wheels, are to be attached to the two longer arms of one of the tri-armed levers, the same being so as to cause the harness to be raised by the movement of the lever in one direction, and to be depressed by its movements in the opposite direction.

The shorter arm, b, of each of the said levers D extends between two cams, E F, which are arranged upon, and so as to be capable of being revolved on, two stationary rods or shafts, c d.

To the side of each cam, and so as to be concentric with the cam-shaft, a gear, e, is fixed, which is designed to revolve the cam by engaging with two vertical racks, G H, arranged as represented in Fig. 3. There is thus combined with each tri-armed lever two cams and two racks. One of these racks has a notch, f, arranged in it, as shown in Fig. 3, the other being without any such notch.

There is also applied to the frame C, and so as to extend down from it in the plane of the two racks, a spring, I, there being such a spring for each pair of racks. A pattern-prism, w, and chain, K, such as is common to fancy looms,

are arranged with respect to such springs, as represented in the drawings.

The next part of the mechanism to be described is what may be termed the "rack-elevating mechanism." A jack or hooked arm, K, turning freely on a rod, h, supported by two arms, i i, extending from a rocker-shaft, k, extends up through a slot, l, made in the bottom piece m of the frame C, and is arranged in the plane of the two racks and the spring thereof.

A connecting-rod, n, projecting upward from and jointed to a joint-piece, o, is applied to a crank, p, affixed upon the lay-shaft B, the said joint-piece being jointed to one of the arms i i.

During each revolution of the lay-shaft a reciprocating vertical motion will be imparted to the two arms i i and their rod h, whereby the several jacks K' will be elevated and depressed simultaneously.

The mechanism for revolving the pattern-prism may be thus explained: On one end of the arbor of such prism is fixed a ratchet, q, against the inner side of which a friction-brake or spring, r, bears, such spring being fastened to the frame C. An impelling or hooked draw-pawl, s, jointed to a lever, t, engages with the ratchet, such lever being connected with the rod h by means of a connecting-rod, u, the whole being as represented.

During the movement of the pattern-chain, its projections will operate against the series of springs I I in the order necessary for the formation of the figure to be woven, the operation being to force each spring inward at the proper time or times, so as to insure it to press its jack inward, in order that during the upward movement of such jack it (the jack) may engage with the inner of the two racks and force it upward. While such rack may be rising the fellow rack will be correspondingly going downward, and the cams will be worked simultaneously, in which case the lower one of them will raise the arm b of the lever D, the other cam revolving, so as to permit such elevation of the arm to take place. This movement of the arm will cause the tri-armed lever to be moved so as to move its harness in one direction.

As soon as the pin of the pattern-chain may have ceased to press upon the spring by which the aforesaid jack was moved inward, such jack will be freed from the pressure of the

spring, and will be thrown back by the action of gravity and out of connection with the rack, so as not to pull it downward.

The two cams will then hold the tri-armed lever rigidly in its position until the next elevation of the jack, which taking place, the jack will be forced up against the outer of the two racks and force it upward, and thus effect movements of the cams such as will move the tri-armed lever in a direction opposite to that in which it was previously moved.

To insure the discharge of each of the hooked jacks from the notch of the rack during an ascent of the jack and rack, each jack has a cam, *v*, fixed to it to act against the end of the slot, *l*.

The above-described invention is very effective and positive in its operation.

I claim—

The above-specified new and useful harness-operating mechanism or combination, consisting of the tri-armed lever *D*, the two cams *E* *F*, the gears *e e*, and racks *G H*, the spring *I*, and the rack-elevating mechanism, the whole being arranged together, and with a pattern-chain and its actuating mechanism, substantially in manner and so as to operate as explained.

WM. R. ANDREWS.
